UNITED STATES PATENT OFFICE

SAMUEL A. LEWIS, OF DERRY, NEW HAMPSHIRE, ASSIGNOR OF FORTY-SEVEN ONE-HUNDREDTHS TO RALPH H. BARKER, OF DERRY, NEW HAMPSHIRE, AND GEORGE W. BARKER, OF ROCHESTER, NEW YORK

SHOE-SOLE SKIVER

Application filed July 9, 1928. Serial No. 291,344.

This invention relates to shoe machinery, and particularly to an improved machine for cutting or skiving the heel end of soles, the object being to provide a machine which will accurately skive the heel end of a sole, whereby it will be properly shaped.

Another object of the invention is to provide a skiving machine for cutting the sides and ends of the heel portion of the sole of a shoe, whereby this heel portion will properly fit a wooden heel or other heel of a shoe when the shoe is being completed.

A further object, more specifically, is to provide a skiving machine for cutting the heel end of a sole in such a way that both the sides and one end are properly chamfered.

In the accompanying drawings,—

Figure 1 is a top plan view of a shoe sole skiver disclosing an embodiment of the invention;

Figure 2 is a sectional view through Figure 1 on the line 2—2;

Figure 3 is a detail fragmentary view partly in section showing how the sole is bent preparatory to cutting;

Figure 4 is a sectional view through Figure 3 approximately on the line 4—4;

Figure 5 is a view similar to Figure 4 but showing the cut-off blade in an operated position;

Figure 6 is a plan view of the die or form shown in Figure 3.

Figure 7 is a perspective view showing the two cutting or skiving knives together with part of the sole of the shoe illustrating how the leather is removed.

Figure 8 is an enlarged perspective view showing the heel end of a sole, said heel end illustrating the chamfered structure resulting from the use of the machine shown in Figure 1;

Figure 9 is a sectional view through Figure 8 on the line 9—9.

In the construction of shoes it is necessary to especially form the heel portion of the sole

to properly receive the heel. This is particularly true in respect to wooden heels and in the present invention a machine has been provided which at one operation skives the heel portion of the sole in a substantially perfect 50 manner. This skiving results in chamfering the edges of the heel portion so that the heel portion will fit properly against the wood heel. When this operation is done by hand it is quite often done inaccurately and poorly, 55 so that certain adjustments and compensating additions must be made to secure a proper fit. In a machine embodying the invention the heel portion is always properly cut and consequently saves much time in the manufacture of the shoe. As shown in Figure 2, the machine embodying the invention is provided with a base structure 1 which may be mounted on any suitable support 2. Arranged on the base 1 is a platform 12 held 65 in place in any desired manner, and straddling this platform is a yoke 3 having a slide-way 4 for purposes hereinafter fully set forth. A pair of guideways 5 is also bolted or otherwise secured to base 1 and each guideway 5 is provided with an upstanding bracket 6. A pin 7 extends through the brackets 6 and through a lever 8 for pivotally mounting this lever, as clearly shown in Figure 2. Lever 8 at one end carries a contact roller 9 bearing against the cam 10 and at the opposite end is pivotally connected at 11 to a sliding block 12' arranged in the head 3' of yoke 3. A screw 13 is connected with the block 12' and extends loosely through the head plate 14 so as to support the spring 15 70 acting on the screw head 16. By reason of this arrangement spring 15 has a tendency to keep the parts substantially in the position shown in Figure 2 with the knife 17 elevated. Whenever the operating or large end 18 of cam 10 is acting on the roller 9 block 12' is forced downwardly so that the knife 17 will be moved in the position shown in Figures 5 and 7, whereby the cut or discarded portion 75

80

85

90

95

19 of sole 20 is severed from the body of the sole. As shown in Figures 1 and 2 the sole 20 is placed on the support or platform 12 with the front or toe end against the adjustable abutment or stop 21, whereby the end of the heel portion of the sole will extend to almost the end 22 of the die or form 23. When the sole is in this position the roller 24 is moved over the end 22 and over the heel portion of the sole, as indicated particularly in Figures 3 and 4. As this roller moves over the heel portion of the sole it is depressed centrally and the edges 25 and 26 are bowed or deflected upwardly, whereby the flat knife 27 may cut off the section or portion 19, as illustrated particularly in Figures 4 and 7. Immediately after the roller passes the forward end of the heel portion 28, as shown in Figure 5, knife 17 will move downwardly to cut off the portion 19 as it cuts the shoulders 29 and 30. This completes the formation of the skived heel portion 28, as shown in Figure 8, thus permitting the sole 20 to be manually removed and a new one substituted. After the new one has been substituted the same operation is performed and so on as long as the machine is in operation. As shown in Figure 6, the die 23 is provided with roughened portions 31 which prevent the sole from slipping during the cutting operation. The roller 24 by reason of its mounting has a very limited or slight resilient action and consequently can be readily forced over the end 22 and then moved, as shown in Figure 3, for depressing the center of the sole. As shown in Figures 1 and 2 the roller 24 is mounted on a yoke 32 which is screwed, riveted or otherwise rigidly secured to a sliding plate 33 slidably mounted in the guide or runways 5. The plate 33 fits rather snugly in the guide 5 but allows a very slight resilient action in order that the roller 24 may pass over the end 22 of die 23. This plate also carries the knife 27 which is removably secured in place by screws. A block 34 is pivotally connected with the plate 33 by pin 35, said block having a threaded bore 36 for receiving one end of the screw 37, the opposite end being threaded into the enlargement 38 of the ring or strap 39 of the eccentric. The eccentric disk 40 is keyed or otherwise rigidly secured to the power shaft 41, which shaft carries a clutch member 42 of a known type and coacting with a clutch member 43. A lever 44 is pivotally mounted at 45 and is provided with an extension 46 for disconnecting the clutch member 43 from the clutch member 42, this action automatically taking place as lever 44 rises. This rising action of lever 44 may be caused by difference in weight on the opposite sides of the pin 45 or may be produced by a spring. A depending member 47 is provided and extends downwardly any desired distance so as to be operated by the foot. A pulley wheel

48 is rigidly secured to the clutch member 43 and is adapted to receive power from any suitable source through a belt or other connecting means. When the machine is in operation pulley 48 is continually rotating and consequently rotates clutch member 43, but this clutch member is normally held out of engagement with clutch member 42 by the extension 46 of member 44. Members 42 and 43 and also member 46 are old and well-known and are used merely as a desirable form of clutch for connecting and disconnecting power from shaft 41. When the machine is operating the sole piece indicated by 20 is placed on the platform 12 and the lever 49 is lowered. This lever carries a presser foot 50 which presses against the sole near the end of die 23 and thereby holds the sole in position while the roller 24 functions. The presser foot 50 may be held in operative position by the weight of lever 49 or if desired, additional removable weights may be used or merely the pressure of the hand of the operator.

If desired, a stamping device could be connected with block 12' in order to stamp the size on the sole each time that knife 17 operates. Also, if desired, a pinch mark could be provided to guide workmen in locating the sole when finishing the shoe.

What I claim is:—

1. A shoe sole skiver, including a substantially U-shaped die having a beveled portion on the inside of the legs of the die, a support for said die, said support having a flat upper surface acting to support the die and prevent the shoe sole from protruding through the die when pressed by a roller, and thereby causing the shoe sole to remain in a certain position for the cutting operation, means for holding a shoe sole so that the heel portion will overlap said die, a depressing roller, means for forcing the depressing roller longitudinally over the die so that the heel portion of said sole will substantially fit said die with certain of the edges projecting beyond the die, and cutting means functioning during the operation of said roller for cutting off said edges.

2. A skiving machine of the character described, including a substantially U-shaped die having chamfered portions on the inner part of the legs of the die and one end, means for supporting a shoe sole so that the heel portion will rest on the die, a roller for pressing the heel portion downwardly between the legs of the die and thereby tilt the end and the sides of the heel portion of the sole, a support for said die, said support having a flat upper surface acting to support the die and prevent the shoe sole from protruding through the die when pressed by a roller, and thereby causing the shoe sole to remain in a certain position for the cutting operation, power means for operating said roller, and

power operating cutting means for cutting that portion of the tilted edges of said heel portion which project beyond the die.

3. A skiving machine for skiving the heel portion of a shoe sole, including a die substantially U-shaped, said die having a beveled corrugated surface on the inner part of each leg merging into a rounded chamfered portion at the end, means for forcing the center of the heel portion of the sole between the leg of said die while the remaining portion is inclined upwardly with part of the remaining portion projecting above the die, a support for said die, said support acting to hold the die in a given position and also to prevent the movement of the sole through said die under the action of said means, and a cutter movable in a plane parallel with the surface of said die for cutting that part of the heel portion projecting above the die.

4. A heel seat fitting machine having a supporting platform formed with a flat upper surface, a substantially U-shaped die formed with a longitudinal centrally-positioned opening therein, said die resting on said flat upper surface, a hold-down roller for holding the heel portion of a sole against said die with the central part extending through said opening and resting on said flat surface, and a cutter positioned to follow said roller to cut the edges of said heel portion while depressed by said roller, said cutter and roller acting simultaneously.

5. A skiving machine of the character described, including a shoe sole support having a flat upper surface, a die carried by said support, said die being formed with a longitudinally-extending slot and roughened chamfered sides merging into said slot, said die having a flat under surface resting on the flat upper surface of said sole support, a roller, means for forcing the roller over that part of the shoe sole resting on said die, said roller functioning to bow transversely the heel portion of said sole, said roller having a portion acting to press part of the sole against said chamfered edges, and a portion through said slot to a point in engagement with said flat upper surface, and a flat knife for cutting the end and sides of the bowed portion of the sole while in a bowed position.

6. A shoe sole skiver, including a die having a slot therein with a portion adjacent the slot chamfered and roughened at the chamfered parts, a roller adapted to pass over said die for forcing the heel portion of a shoe sole into said slot and against said chamfered parts, means for holding a shoe sole in position so that the heel portion will fit over said die, whereby when said roller moves over the die it will bow the heel portion of the sole and force part thereof into said slot and the remaining part against said chamfered parts with the ends and sides projecting above the die, a support for said die acting to prevent

the movement of said sole through said slot, a reciprocating power member for actuating said roller, a knife secured to said reciprocating member, said knife having an edge spaced a short distance from said roller, said knife acting to cut the edges of the heel portion of said sole which project beyond the die, and a power-operated knife moving at right angles to the first-mentioned knife for severing certain parts of the sole after the first-mentioned knife has functioned.
